UNITED STATES PATENT OFFICE.

CARL FERDINAND GROHMAN, OF GÜSTROW, GERMANY.

DEVICE FOR EMPTYING COLLECTING-BOXES OF HARVESTING-MACHINES.

SPECIFICATION forming part of Letters Patent No. 716,706, dated December 23, 1902.

Application filed May 18, 1901. Serial No. 60,868. (No model.)

To all whom it may concern:

Be it known that I, CARL FERDINAND GROHMAN, a subject of the Grand Duke of Mecklenburg-Schwerin, residing at Güstrow, in the 5 Grand Duchy of Mecklenburg-Schwerin, Germany, have invented certain new and useful Improvements in Devices for Emptying the Collecting-Boxes or Receivers of Potato and Similar Harvesting Machines, of which the 10 following is a specification.

My present invention relates to a device designed to empty the collecting-box or receiver of potato and similar harvesting machines.

15 The characteristic feature of my invention is the automatic opening of the closing device of the collecting-box, which is effected by the rotation of the main shaft or axle.

In the accompanying drawings one form of 20 my invention is represented as applied to a potato-harvesting machine.

Figure 1 is a side elevation of such a machine, showing the collecting-box at the back end of the same. Fig. 2 is a side elevation 25 of the collecting-box and its operating mechanism. Fig. 3 is a cross-section through the collecting-box, showing the operating parts in elevation; and Fig. 4 is a plan of Figs. 2 and 3.

30 The collecting-box 1 is fitted to the hinder end of a potato-digging machine of the usual form, which bears on the side beams 3 a plow-share and above this a rapidly-rotating drum, which throws the potatoes dug up by the 35 plowshare into a bucket-elevator, by means of which they are carried onto the oscillating sieve 18, from which they fall through the wide-meshed portion of the sieve into the collecting-box forming the essential feature of 40 the present invention.

The collecting-box 1 is supported in the hanger-bearings 2, secured to the extended side beams 3 of the machine. On both sides of the collecting-box the flaps or doors 4 are 45 provided, being jointed together by means of the arms 5 to the rods 6. In the bearings 7, which are supported by the side beams 3, is journaled a shaft 8, on which are secured two levers 9 9^a, which are secured together. To 50 these levers 9 9^a the rods 6 are so secured that they can be easily disconnected. On the shaft 8 are also mounted two levers 10

10^a, which are rigidly secured together, by which levers the reciprocating motion of the levers 9 9^a is obtained. Underneath the shaft 55 8 and at right angles to the same is provided a shaft 12, journaled in the bearings 11, secured on the side beams 3, and on this shaft is secured the chain-wheel 13, which is driven by a chain from the main shaft or axle of the 60 machine. On the shaft 12 is also secured a lever 14. Another lever 15, which is similar to the lever 14, is loosely mounted on the shaft 12 and is held by a pin 16, secured in and projecting at both ends beyond the shaft 12, 65 which engages in a groove in the enlarged hub of the lever 15, a spring 17 being provided to keep the hub and pin in engagement, as shown in Fig. 3 of the drawings.

Between the shafts 8 and 12 and the collecting-box is suspended an oscillating sieve 18, which is oscillated by a rod 30. The bearings of this sieve are provided on the side beams of the machine.

If now it is desired to empty the collecting-box 1 on one side, the closing device or door 4 on the other side is closed, for which purpose the pins provided on the arm 5 are caused to engage with the hooks 19, connected to the side beam of the machine. The rod 6 of the 80 other closing device of the collecting-box is secured to the corresponding lever 9. When the closing device or door 4 is closed, the lever 9 is moved into its topmost position, and the rod 6 takes the position shown in dotted 85 lines in Fig. 3. As the shaft 12 rotates the lever 15 will strike against the lever 10^a and raise the same into the position shown in Fig. 3. During this rotation of the lever 10^a the lever 9, which is secured on the same shaft as 90 the lever 10^a, will be moved from its vertical position into that shown in full lines in Fig. 3, again opening the closing device or door 4 by means of the rod 6, so that the contents of the collecting-box will fall out onto the ground. 95 As the levers 14 and 15 are arranged at an angle of ninety degrees, the lever 14 will now engage with the lever 10 and move it into its topmost position again, thus closing the door 4 again. The lever 15 is arranged, as described, 100 so as to be movable, to allow it to be moved in certain cases in the same direction as the lever 14, by which can be effected the periodical opening and shutting of the collecting-box.

This operation will be repeated continuously as long as the machine remains in motion. It will be seen, therefore, that the potatoes will be alternately collected in and removed 5 from the box 1. If it is desired to empty the potatoes on the other side of the machine, this can be done by placing the arm 5 and lever 6 on the left side of Fig. 3 into the same position as that shown on the right side.

10 What I claim, and desire to secure by Letters Patent of the United States, is—

1. In a harvesting-machine for potatoes and the like, the combination of a collecting-box 1 supported in bearings secured to the frame of 15 the machine, closing devices 4 at the ends of said collecting-box, an arm 5 secured to each closing device, a rod 6 jointed to each arm 5, levers 9, 9^a adapted to be jointed to the rods 6, means for reciprocating said levers 9, 9^a, 20 substantially as and for the purpose described.

2. In a harvesting-machine for potatoes and the like, the combination of a collecting-box 1 pivotally supported in bearings secured to the frame of the machine, closing devices 4 at the ends of said collecting-box, an arm 5 secured to each 25 closing device, a rod 6 jointed to each arm 5, a shaft 8 arranged parallel to the frame of the machine, levers 9, 9^a rigidly connected to each closing device, a rod 6 jointed to each arm 5, a shaft 8 arranged parallel to the frame of the machine, levers 9, 9^a rigidly connected

together and mounted on the shaft 8, levers 30 10, 10^a likewise mounted on said shaft 8 and means for reciprocating the said levers 10, 10^a and thus the levers 9, 9^a, substantially as and for the purpose described.

3. In a harvesting-machine for potatoes and the like, the combination of a collecting-box 1 pivotally supported in bearings secured to the frame of the machine, closing devices 4 at the ends of said collecting-box, an arm 5 secured to each closing device, a rod 6 jointed to said 40 arms 5, a shaft 8 arranged parallel to the frame of the machine, levers 9, 9^a rigidly connected together and mounted on the shaft 8, levers 10, 10^a rigidly secured together and likewise mounted on said shaft 8, a shaft 12 arranged 45 at right angles to the shaft 8, levers 14, 15 arranged at a right angle to each other and adapted when the shaft 12 is rotated to alternately raise and lower the levers 10, 10^a and consequently reciprocate the shaft 8 and the 50 levers 9, 9^a, substantially as and for the purpose described.

In testimony whereof I have hereunto set my hand in the presence of two witnesses.

CARL FERDINAND GROHMANN.

Witnesses:

GUSTAV WEBER,
PAUL FRIEDR. DÜHRKOOP.
